ATTACHMENT FOR BARBERS' CHAIRS

Filed Oct. 18, 1928

UNITED STATES PATENT OFFICE

CHARLES W. MOBLEY, OF BARNESVILLE, GEORGIA

ATTACHMENT FOR BARBERS' CHAIRS

Application filed October 18, 1928. Serial No. 313,269.

This invention relates to improvements in barbers' chairs of that type which are provided with displaceable head-rests having an elongated supporting standard. The head-rest is provided with means for adjustably mounting the same on the back of chair to be used in shaving operations; when the chair is employed in a hair-cutting operation the head-rest is dismounted and placed aside. 5 The object of the present invention is to provide an attachment mounted on the chair to hold the head-rest when not in use. By employing the attachment the head-rest can be deposited in an out of the way place convenient to the barber and the liability of accidentally knocking the head-rest to the floor to its injury is avoided. Means are provided for mounting the attachment on an ordinary chair without structural changes in the latter. 10 The attachment and the means for mounting the same are described in detail hereinafter and illustrated by the accompanying drawings.

In the drawings, in which similar reference numbers designate corresponding parts, 25 Figure 1 is a vertical sectional view of part of a barber's chair with the attachment mounted thereon and the head-rest positioned in the holder of the attachment; only so much 30 of the chair is shown as is necessary to illustrate the attachment and its use.

Figure 2 is a sectional view on the line 2—2 of Figure 1;

Figure 3 is a longitudinal sectional view 35 through the holder and an attached bracket part;

Figure 4 is a transverse sectional view of the holder, on the line 4—4 of Figure 3;

Figure 5 is a detail view, broken away in 40 parts, of a modified form of the means for mounting the attachment on the chair seat; and

Figure 6 is a detail view, showing one of the members of the mounting shown in Figure 5.

Referring to the drawings in detail, 10 designates the annular metal frame of the seat of a barber's chair of well known pattern, pivotally mounted on the pedestal 11. As the 50 pivotal mounting forms no part of the pres-

ent invention, it is only indicated diagrammatically in the drawings and requires no particular description. The annular seat frame includes a horizontal flat part 12 and a peripheral depending flange 13. The arms 55 (not shown) of the chair are attached to the flat part of the frame by bolts, such as at 14. This bolt extends through the seat and is held in place by the nut 15 turned on the lower end of the bolt to abut the under side 60 of horizontal flat part 12 of the seat. To provide a clamp for the attachment, the bolt 14 extends below the nut 15 and turned on its extremity is a second nut 16, the bolt and the two nuts providing the clamping means. 65

The holder 17 is a casing formed of sheet metal bent to a flattened tubular shape with the edges slightly separated to form a longitudinal slot 18 extending along the casing in one of the flattened sides thereof. The 70 holder is provided at one end with a flared mouth 19 and the other end is closed by a cushion 20 held in place by flanges 21 inwardly turned from the wall of the casing. A short distance from the mouth of the holder, a 75 tongue 22 is struck inwardly from the flattened wall of the casing opposite to the side having the longitudinal slot 18. In the mounted position of the holder, that side having the tongue 22 is uppermost. 80

The means for mounting the holder on a chair seat include a two-part bracket formed of two adjustably connected angle bars. One of these angle bars comprises a long arm 23 and a short arm 24, the two arms being in 85 oblique relation. The long arm 23 of this angle bar extends along the upper side of the holder and is attached thereto by the bolts 25 extending through the longitudinal slots 26 in the arm and through circular openings 90 in the adjacent wall of the holder. By means of nuts 27 on the inner ends of the bolts the arm 23 and the holder can be clamped together, the slots 26 in the arm permit relative adjustment of the holder and arm. The 95 elongated arm 23 not only forms part of the bracket member, but also serves to reinforce the tubular holder. In the short arm 24 of the angle bar is a longitudinal slot 28.

The other or upper angle bar comprises the 100

relatively oblique arms 29 and 30, respectively, the angular relation of the two arms being such that the bar fits the angle formed by the horizontal seat portion 12 and the depending flange 13. The angle bar 29—30 is secured to the seat by the clamp formed by the bolt 14 and the nuts 15 and 16. The lower end of the bolt extends through the arm 29 of the upper angle bar and the arm is clamped 10 between the nuts 15 and 16. Set-screws 31 passing through the slot 28 in the arm 24 of the lower angle bar and turned into threaded openings of the arm 30 of the upper angle bar hold the two angle bars together. By 15 means of the slot 28 and the set-screws 31 passing therethrough, the two members of the two-part bracket can be relatively adjusted so that the mounting for the holder can be adjusted to accommodate chair seats of 20 different patterns.

With the holder mounted as indicated in Fig. 1, it extends in an inclined position beneath the chair seat, at one side of the latter. The length of the tubular holder is slightly 25 less than the length of the supporting standard 32 of the head-rest, so that when the standard is shoved into the holder the head-rest proper does not strike the mouth 19 of the holder. The inclination of the holder is 30 such that the supporting rod slides readily into the same. When the supporting standard is shoved into the holder the inner end of the standard strikes the cushion 20 and the shock is absorbed thereby. The tongue 35 22 projecting into the holder guides the supporting standard so that rack teeth of the standard will not strike the nuts 27 as the standard enters the holder to be injured thereby. The slot 18 extending along the under 40 side of the positioned holder permits the escape of extraneous matter that might collect in a closed holder.

As shown in Fig. 1, the holder is mounted on a side of the chair seat, but means are 45 provided, as shown in Figs. 5 and 6, for mounting the holder on the rear part of the seat. A yoke plate 33 is secured beneath the under rear side of the chair seat by the opposite chair arm bolts 34 extending through the 50 openings 35 in the ends of the yoke plate, the ends of the plate being clamped between the nuts 36 and 37 on the lower ends of the bolts 34. Extending through the central opening 38 of the yoke plate is the bolt 39 provided 55 with the nut 40 for clamping the upper angle bar of the two-part bracket to the yoke plate. By this means the holder is mounted at the central rear part of the chair seat.

What I claim is:

60 1. In an attachment for the seat of a barber's chair, the combination with an elongated tubular holder adapted to receive the supporting standard of a head-rest, of an angle-bar having a long arm attached to and extending longitudinally a considerable length

of the holder, said angle-bar also having a short arm oblique to the long arm and projecting from the holder adjacent to the receiving end thereof, and means for attaching the short arm of the angle-bar to the outer part 70 of the chair seat to decline the holder beneath the seat.

2. In an attachment for the seat of a barber's chair having a depending peripheral flange, the combination with an elongated tubular holder adapted to receive the supporting standard of a head-rest, of an angle-bar having a long arm attached to and extending longitudinally a considerable length 75 of the holder, said angle-bar also having a short arm oblique to the long arm and projecting from the holder adjacent to the receiving end thereof, and a second angle-bar adapted to fit the inner angle of the seat and depending flange, means for clamping one 80 of the arms of the second angle-bar to the chair seat with said second angle-bar fitting the inner angle of the chair seat and the depending flange, and means for attaching the other arm of the second angle bar to the short arm of the first angle-bar, said angle-bars constituting a mounting for positioning the holder beneath the seat with its receiving end adjacent to the periphery of the seat and the holder declined toward its other end. 85

3. In an attachment for barbers' chairs, the combination with an elongated tubular holder adapted to receive the standard of a head-rest, of an angle bar having an arm extending along the holder, a bolt extending through the wall of the holder and the adjacent arm of the angle bar and extending into the holder, a tongue projecting into the holder and operating to guide the entering standard to clear the inner end of the bolt, and means for attaching the other arm of 90 the angle bar to a chair. 100
